DES. 1939

Edward K. Butler, of Boston, Mass.

Letters Patent No. 11939-Dated May 10th 1864.

Design for a Slipper Pattern.

The schedule referred to in these Letters Patent and making part of the same.

To all persons to whom these presents shall come,

Be it known that I, Edward K. Butler, of Boston, in the County of Suffolk, and State of Massachusetts, have invented or produced a new and ornamental design for a Slipper upper, and do hereby declare the same to be fully represented in the accompanying drawing, and described in the following specification.

The ground work A of the design has an external form which is a parabola, or a close approximation thereto. At the base of the parabola or ground there is a broad strip or band B whose color is to be different from that of the rest of the ground, or in which there is a bunch of flowers C, the whole having the form or forms and character as exhibited in the drawing.

This design is intended to be printed on cloth to be used for the upper of a slipper.

I claim The said design, as provided with the band B, making part of the ground work, and as having a bouquet representation of flowers in the remaining portion of the ground all substantially as specified.
